[57] ABSTRACT

A railway car door of the sliding plug type is positioned within the door frame arrangement in the side of a car. The door frame arrangement comprises horizontally spaced side posts, an upper horizontally extending side plate structure and a lower side sill. The door posts which define the sides of the opening are provided with flanges which cooperate with flanges on the door to substantially close the door openings. The flanges on the door and on the side posts are also provided with a water drain structure including vertically extending lips which project outwardly with respect to the door opening and cooperate with waterguards supported on the post flanges to provide vertically extending drain troughs at the corners of the door posts.

WATER DRAIN STRUCTURE FOR RAILWAY CAR DOOR ARRANGEMENT

BACKGROUND OF THE INVENTION

1. Field of the Invention

The field of art to which this invention pertains is railway boxcars having door opening structures of the type adapted to contain a laterally moveable and slideable door.

2. Description of the Prior Art

The prior art is disclosed in U.S. Pat. Nos. 2,447,846; 2,522,761; 2,580,804; 2,780,180; 2,974,376; 3,091,493; 3,099,230; 2,237,573; 3,339,323 and 3,768,422.

SUMMARY OF THE INVENTION

It is a prime object of the present invention to provide an improved water drain arrangement for removing rainwater from a door frame and for preventing the entrance of such moisture into the interior of the car. The invention is directed particularly toward the door frame having horizontally spaced vertically extending door posts, a lower side sill and an upper plate structure defining the door opening. A sliding and laterally moveable door is adapted to fit into the door opening structure and includes at opposite ends flanges which extend and overlap parallel flanges on the door posts. The door post flanges and the door flanges are laterally spaced and each door flange includes a vertically extending lip projecting inwardly toward the parallel post flanges with the lips terminating laterally to one side of the door opening. The waterguard includes a vertical web and a flange connecting the said web to the door post flange with the guard flange having its end portion substantially close to the terminal edge of the lip 59. The waterguard also includes another flange extending in the opposite direction and being connected to the first flange of the waterguard by means of the vertical web. The waterguard and the lip provide a vertically extending drain trough and also provide means for preventing the entrance of moisture or rain into the door opening. The door on one side thereof also further includes flange portions providing a serpentine path arrangement with a flange of the door post to also prevent the entrance of moisture into the interior of the car.

BRIEF DESCRIPTION OF THE DRAWINGS

FIG. 1 is a side elevational view, with portions thereof broken away, illustrating an improved door frame arrangement door and water drain construction;

FIG. 2 is a cross sectional view taken substantially along the line 2—2 of FIG. 1;

FIG. 3 is a cross sectional view taken substantially along the line 3—3 of FIG. 1; and

FIG. 4 is a cross sectional view taken substantially along the line 4—4 of FIG. 1.

DESCRIPTION OF THE PREFERRED EMBODIMENT

As disclosed in FIG. 1, a railway car side 10 includes side wall sheathing 11, an upper side plate structure 12, a side sill 13 and vertically extending laterally spaced door posts 14 defining a door opening 15. The side plate structure 12 at the upper end of the door opening 15 also includes an upper header member 16. Espe-

cially as shown in FIG. 4, a track guide member 17 is connected to the header member 16 and with a horizontally extending track member 18 provides suitable track means for a crank and roller structure to be described. The upper plate structure 12 also has connected thereby an angle 19 which supports a U-shaped gutter element 20 consisting of vertically extending flanges 20'. The gutter element 20 also includes drain shelves or portions 21 adapted to drain water through openings 22 projecting through lateral flanges 23 of the door post 14. Similar flanges 24 of the posts 14 are connected by vertical webs 25.

As shown in FIG. 1, a horizontal track 26 supports for sliding movement thereon a door 27. The door 27 consists of metal plate or sheathing 28 provided at horizontally spaced ends with end wall members 29 of tubular construction. The end wall members 29 include vertically and laterally extending side walls 30 and 31. Vertical door flanges 32 project respectively outwardly from and in perpendicular relation to the outer walls 30. Each of the door flanges 32 includes laterally extending bent flange portions 33. As best shown in FIG. 2, the left hand side of the door 27 is provided with a laterally extending outer wall portion 34 connected at one end to one of the bent flange portions 33 and further includes a diagonal portion 35 integral with a laterally extending portion 36 in turn integral with an outer plate member 37 which is suitably connected to the left hand outer end wall member 29. A V-shaped corner element 38 is connected to the adjacent portion of the web 25 and lateral flange 23 of the left hand post 14. The corner element 38 includes a diagonal portion 39 which with the diagonal wall 35 forms a narrow serpentine space 40 extending vertically substantially the length of the door 27.

Referring now to FIG. 1, a door operating member 41 is disclosed. This operating mechanism may be similar to that described in U.S. Pat. No. 3,653,153 granted Apr. 4, 1972 and is herein only generally described. The mechanism 41 includes horizontal locking bolts 42 which may be horizontally moved into locking engagement with openings (not shown) provided in the door posts 14. Vertical locking bolts 43 are moveable vertically into locking engagement with openings in brackets (not shown) provided in the side sill 13 and in the upper plate structure 12. The mechanism 41 is suitably actuated by means of a manual handle 44. A vertical actuating member 45 suitably actuates the locking bolts 42 and 43 provided at the upper end portion of the door. A linkage 46 is provided with a clevis member 47 which during horizontal movement of the linkage 46 rotates a vertical pipe or actuating rod 48. The lower end of the rod 48 includes a conventional crank arm 49. Similarly an upper crank arm 50, as best shown in FIG. 4, is also connected to the upper end of the rod 48. The lower crank arm 49 is suitably connected to a roller support 51 of conventional design which is supported on the track 26. The upper crank arm 50 is connected to an upper roller 52 which, as best shown in FIG. 4, is suitably guided and moveable in the track guide member 71 and track element 18. The door also includes a plurality of transversely extending hat-shaped beams 53 which extend across the door and are connected to the wall 31 of the end wall members 29.

As best shown in FIG. 1, the left hand side of the door 27 has connected thereto a swivel pedestal 54 provided

at its lower end with a roller support 55. The upper left hand section of the door 27 is also supported by means of a roller support assembly 56 suitably contained within the track guide member 17 and track element 18. The outer walls 30 also include portions 57 integral with a flat flange section 58 from which a diagonally extending lip 59 projects. The section 58 and lip 59 are substantially coextensive vertically with the door 27 with the lip portions 59 terminating to one side of the opening 15. The flange section 58 is suitably riveted as indicated at 60 to the vertical door flanges 32. The door posts 14 further include inner vertically extending flanges 60' which extend parallel to the vertical door flanges 32 and define sides of the door opening 15. A pair of waterguards are generally designated at 61 and extend vertically and are substantially coextensive with the door 27 and lips 59. The waterguards 61 comprise guard flanges 62 suitably welded to the flanges 60'. The waterguards 61 are of S-shaped configuration including flanges 63 suitably connected to laterally extending webs 64 in a manner wherein said guard flanges 62 and 63 extend in opposite directions. The configuration of the drain guards 61 and lips 59 provide at opposite sides of the door vertically extending drain troughs 65, and in the corners of the connected flanges 23 and 60', vertically extending troughs 66.

THE OPERATION

The operation of the present door mechanism is similar to that described in the aforementioned U.S. Pat. No. 3,653,153 and need not be further described. FIGS. 1, 2 and 4 disclose the closed position of the door which of course may be moved laterally outwardly from its plug or closed position whereupon it can be rolled to one side of the door opening on the track 26. In the closed position the gutter element 20 is adapted to suitably catch and channel rain water, directed against the upper edge of the door, through the openings 22 downwardly through the door posts 14. In the closed position also the vertical door flanges 32 are in engagement with the guard flanges 63 of the waterguard 61. Water that may enter through the serpentine space 40 on one side of the door and along the outwardly bent portion 33 of the other side of the door courses downwardly through the drain troughs 66. Such moisture as may enter between the guard flanges 63 and the vertically door flanges 32 runs inwardly along the flanges 32 where it then is caught and deflected by means of the lips 59 downwardly through the vertical troughs 65. In this manner effective sealing is provided since moisture is restricted from moving through the door opening, the surfaces of the component parts as described serving to direct the water downwardly following the path of least resistance to the bottom of the troughs 66 and 65 whereupon the moisture drains from the bottom of said doors downwardly to the ground.

It has been determined by this particular arrangement a very effective seal is provided which is not dependent upon resilient compositions which soon deteriorate and which cannot long endure the strenuous service to which doors of railroad cars are subjected. Also the construction is such that it is not required to manufacture the same to the very fine dimensional tolerances necessary for normal effective sealing. In a structure of this type, due to extreme expansions and contractions caused by weather changes, such tolerances

cannot be maintained and the present invention does not require the same.

What is claimed is:

5 1. In a railway car having a side wall including a door opening, said opening being defined by a side sill, horizontally spaced vertical door posts and an upper side plate structure, a track on said car below said opening, and a door slideably supported on said track and laterally moveable into said opening for closing the same, the improvement of a water drain arrangement comprising:

each door post including a first post flange extending vertically and laterally inwardly toward said side wall,

a second vertical post flange connected to each said first post flange and extending parallel to said side wall and terminating adjacent said door opening, said door having vertically extending laterally spaced and relatively parallel end wall members, laterally extending vertical side walls connecting said end wall members,

vertical door flanges connected to and projecting outwardly from said vertical side walls in substantially parallel relation to said second post flanges,

vertical drain lip elements extending substantially the length of said door flanges and projecting laterally inwardly toward said second post flanges, said drain lips terminating outside of said door opening,

waterguards coextensive with said lips each including a vertical web extending laterally between each said second post flange and each said first door flanges,

said waterguards being supported between said first door flanges and each including first and second guard flanges connected to and projecting from said web in opposite directions with respect thereto and substantially parallel relative to said second post flanges and first door flanges, and

one of each of said guard flanges terminating adjacent to each said drain lips to thereby form relatively tubularly shaped vertical drain troughs.

2. The invention in accordance with claim 1, wherein

said guard flanges terminating adjacent to each of said drain lips are connected to said second post flanges, and

said other guard flanges are engaged by said vertical door flanges in the closed position of said door.

3. The invention in accordance with claim 2, said water guard webs and said other guard flanges being spaced from said first post flange to provide second vertical tubular drain troughs horizontally spaced from said first troughs.

4. The invention in accordance with claim 3, one of said door flanges including a laterally extending vertical outer wall having a portion extending diagonally and another connected portion extending parallel to one of said laterally extending vertical side walls,

said first post flange having a corner element including a diagonally extending wall portion forming with said diagonal portion and said parallel portion a serpentine vertical space.

5. The invention in accordance with claim 1,

one of said door flanges having a laterally extending vertical outer wall connected thereto, said outer wall having a serpentine configuration and with said first post flange forming a vertically extending serpentine space.

6. The invention in accordance with claim 5, said first post flange having a corner element including a diagonally extending wall portion forming with said serpentine outer wall said serpentine

space.

7. The invention in accordance with claim 1, including a horizontal gutter member with an upper opening supported on said upper plate structure, drain openings on said first post flanges, and drain portions on said gutter member communicating with said drain openings.
